ALBERT L. HUNT AND JOHN L. NAUJOCK, OF MILWAUKEE, WISCONSIN.

AUTOMATIC REVERSING MECHANISM.

Application filed July 23, 1926. Serial No. 124,368.

This invention relates to improvements in automatic reversing mechanisms.

Many machines in operation require intermittent rotation in opposite directions, as in laundry and other machinery, and it is one of the objects of the present invention to provide a reversing mechanism which will automatically transmit motion intermittently in opposite directions in a very simple manner.

10 A further object of the invention is to provide an automatic reversing mechanism which is adapted to be easily connected to any machine requiring reverse operation.

15 A further object of the invention is to provide an automatic reversing mechanism which may be manually controlled to start or stop the mechanism or to permit adjusting the driven mechanism to a predetermined position.

20 With the above and other objects in view, the invention consists of the improved automatic reversing mechanism and its parts and combinations as set forth in the claims and all equivalents thereof.

25 In the accompanying drawings in which the same reference characters indicate the same parts in all of the views:

Fig. 1 is a top view of the improved reversing mechanism, the top portion of the 30 casing being removed, the view also indicating by dotted lines a portion of a washing machine driven by the mechanism;

Fig. 2 is a transverse sectional view thereof taken on line 2—2 of Fig. 1;

35 Fig. 3 is a similar view taken on line 3—3 of Fig. 1;

Fig. 4 is likewise a transverse sectional view taken on line 4—4 of Fig. 1.

Fig. 5 is a top view of the machine, parts 40 broken away to show interior construction and the worm wheel being removed;

Fig. 6 is an outside view of the machine; and

45 Fig. 7 is a transverse sectional view taken on line 7—7 of Fig. 6.

Referring to the drawings, the numeral 10 indicates a frame which forms the lower portion of a casing, and 11, the upper portion of said casing, is bolted thereto to enclose most of the gears of the mechanism. A drive shaft 12 journaled in and extending through the frame and casing is provided with a gear wheel 13 on its outer end, which is in mesh with a pinion 14 mounted on the shaft of an electric motor or other source of power 15 and is driven thereby. Within the

casing and adjacent one end thereof the shaft 12 is provided with pinions 16 and 16', of different diameters, and also within the casing adjacent its opposite end, the shaft 60 is provided with a pinion 17. A counter shaft 18 journaled in the frame above the drive shaft 12 has mounted fast thereon and medially of its length a worm 19 and at its opposite end portions and fast thereon, pinions 20, 21 and 21' respectively, the pinions 21 and 21' being of different diameters, as clearly shown in Fig. 1. The pinion 20 is in mesh with the pinion 16', and pinion 21' is in mesh with the pinion 17 to drive the 70 shaft 18 at its opposite end portions and equalize the strain. A reversing shaft 22 extending through and journaled in the frame 10 may carry gear wheels 23 on its opposite ends which mesh with gears 24 forming part of the machine 25 to be driven. Within the casing and adjacent the opposite ends thereof, the shaft 22 has loosely mounted thereon gear wheels 26 and 27 having inner clutch hubs 26' and 27' for clutching the 80 respective gears 26 and 27 alternately to the shaft 22. The clutch hubs or members are provided with inwardly extending actuating fingers 28 which are alternately engaged by the opposite conical ends 29 of a reciprocal 85 sleeve member 30 loosely mounted on the shaft 22 and movable to clutch the gear 26 or 27 to the said shaft 22. The gear wheel 26 is in mesh with the pinion 16, while the gear wheel 27 is in mesh with the pinion 21 to 90 provide for reversing direction of rotation of the shaft 22.

The conical end portions of the sleeve form annular shoulders 29', between which one end portion 31 of a lever member 32 extends. 95 Said end portion 31 is of sufficient width to engage and move the reciprocal sleeve to engage the clutch fingers 28. The lever member 32 is fulcrumed on the lower portion of the casing, and extends outwardly therefrom, and is provided with a handle 33 for manual manipulation. The lever 32 is also provided with a longitudinally extending slot 34 for receiving the wrist pin and roller 35 of a worm wheel 36 which is positioned above 105 the lever 32. A short vertically extending shaft 37 extending through the upper portion of the casing is formed with a lower eccentric portion 38 upon which the worm wheel 36 is journaled. A cranked handle 39 mounted fast on the upper end portion of the shaft permits convenient turning of said

shaft and the eccentric portion thereof to swing the worm wheel 36 out of mesh with the worm 19, and when thus disengaged the lever 32 may be swung laterally to move the clutch sleeve 30 to engage or disengage either clutch finger 28. A ball, spring and recess latch 39' normally holds the eccentric 38 in a neutral position to maintain the worm wheel 36 in mesh with the worm 19.

- 10 In operation, the shaft 12 will be rotated by the motor, and through the intermediary of the pinions and gears 16, 20 and 17, 17' and 21, the gear wheels 26 and 27 will be continuously rotated in opposite directions.
- 15 The worm will rotate the worm wheel, and the wrist pin and roller 35 will oscillate the lever and move the clutch sleeve 30 to engage one clutch finger, and then the other alternately in successive order and alternately clutch the reversely rotated gears 26 and 27 to the shaft 22, and thus alternately reverse the direction of rotation of said shaft 22 and the machine to which it is connected.

From the foregoing description, it will be seen that the automatic reversing mechanism is of very simple construction, and is well adapted for the purpose described.

What we claim as our invention is:

1. An automatic reversing mechanism, comprising a frame, a drive shaft journaled thereon, a countershaft journaled on the frame, a reversing shaft journaled on the frame and having means for transmitting motion therefrom, means for rotating the drive shaft, pinions gearing the drive shaft to the countershaft, gear wheels loosely mounted on the reversing shaft, one of said gear wheels being in mesh with one of the pinions on the drive shaft and the other gear wheel being in mesh with one of the pinions on the countershaft for receiving rotation in a reverse direction, shaft clutching means connected to the gear wheels, a clutch sleeve slidably mounted on the reversing shaft and having conical end portions for actuating the shaft clutching means of the gear wheels and having spaced shoulders, a lever member

fulcrumed on the frame and extending between the shoulders and having an elongated slot, an eccentric shaft journaled on the frame, a worm wheel journaled on the eccentric shaft and having a wrist pin which enters the elongated slot, a worm mounted on the countershaft and in mesh with the worm wheel, and means for turning the eccentric shaft to swing the worm wheel into and out of gear with the worm.

2. An automatic reversing mechanism, comprising a frame, a drive shaft journaled thereon, a countershaft journaled on the frame, a reversing shaft journaled on the frame and having means for transmitting motion therefrom, means for rotating the drive shaft, pinions gearing the drive shaft to the countershaft, gear wheels loosely mounted on the reversing shaft, one of said gear wheels being in mesh with one of the pinions on the drive shaft and the other gear wheel being in mesh with one of the pinions on the countershaft for receiving rotation in a reverse direction, shaft clutching means connected to the gear wheels, a clutch sleeve slidably mounted on the reversing shaft and having conical end portions for actuating the shaft clutching means of the gear wheels and having spaced shoulders, a lever member fulcrumed on the frame and extending between the shoulders and having an elongated slot, an eccentric shaft journaled on the frame, a worm wheel journaled on the eccentric shaft and having a wrist pin which enters the elongated slot, a worm mounted on the countershaft and in mesh with the worm wheel, said lever member also extending outwardly for manual manipulation, and a cranked arm mounted on the upper end portion of the eccentric shaft for turning said shaft to swing the worm wheel out of mesh with the worm.

In testimony whereof, we affix our signatures.

ALBERT L. HUNT.
JOHN L. NAUJOCK.
